DESIGN FOR A VANITY CASE FOR AUTOMOBILES

James J. O'Neill, Oakland, Calif.

Application February 4, 1936, Serial No. 60,969

Term of patent 14 years

To all whom it may concern:

Be it known that I, James J. O'Neill, a citizen of the United States, residing at Oakland, California, have invented a new, original, and ornamental Design for a Vanity Case for Automobiles, of which the following is a specification, reference being had to the accompanying drawing, forming part thereof.

I claim:

The ornamental design for a vanity case for automobiles substantially as shown and described.

JAMES J. O'NEILL.
